CLAIM

The ornamental design for a whiteboard wallet for making notes and storing credit cards as shown and described.

DESCRIPTION

1. Whiteboard wallet for making notes and storing credit cards

1.1 : shows a top view of the whiteboard wallet for making notes and storing credit cards in an open configuration;

1.2 : shows another top view thereof;

1.3 : shows a top view thereof;

1.4 : shows a front view of the whiteboard wallet for making notes and storing credit cards in a partially open configuration;

1.5 : shows a front view of the whiteboard wallet for making notes and storing credit cards in a partially open configuration;

1.6 : shows a front view of the whiteboard wallet for making notes and storing credit cards in a closed configuration; and

1.7 : shows a left view thereof.

The claimed design shows a whiteboard wallet having credit cards storage, in multiple configurations. The dashed broken lines in the drawings depict environmental subject matter and portions of the article that form no part of the claimed design. The written notes depicted in thick dashed lines depict environmental subject matter and form no part of the claimed design.
